CLAIM

The ornamental design for a smart watch, as shown and described.

DESCRIPTION

FIG. 1 is a front and right-side perspective view of a smart watch, showing our new design;
FIG. 2 is a rear and left-side perspective view thereof;
FIG. 3 is a front elevational view thereof;
FIG. 4 is a rear elevational view thereof;
FIG. 5 is a left-side elevational view thereof;
FIG. 6 is a right-side elevational view thereof;
FIG. 7 is a top plan view thereof;
FIG. 8 is a bottom plan view thereof;
FIG. 9 is an enlarged view of a portion of the smart watch shown enclosed by the broken lines labeled **9** in FIG. 1; and,
FIG. 10 is an enlarged view of a portion of the smart watch shown enclosed by the broken lines labeled **10** in FIG. 2.
The evenly spaced broken lines depict portions of the smart watch that form no part of the claimed design. The long-short dashed lines encircling portions of the smart watch in FIGS. 1, 2, 9 and 10 indicate enlargements and form no part of the claimed design.
